(57) **CLAIM**

The ornamental design for a shoe, as shown and described.

DESCRIPTION

FIG. 1 is a perspective view of a shoe showing my new design.

FIG. 2 is a left side elevational view thereof; and,

FIG. 3 is a right side elevational view thereof.

The broken lines showing a typical shoe are for illustrative purposes only and form no part of the claimed design.

1 Claim, 1 Drawing Sheet

FIG. 1

FIG. 2

FIG. 3
